UNITED STATES PATENT OFFICE.

CHARLES DRAKE, OF MANNINGTON, WEST VIRGINIA.

DERRICK.

Application filed June 2, 1921. Serial No. 474,336.

To all whom it may concern:

Be it known that I, CHARLES DRAKE, a citizen of the United States, and a resident of Mannington, in the county of Marion and State of West Virginia, have invented a new and useful Improvement in a Derrick, of which the following is a full, clear, and exact description.

My invention relates to derricks and more particularly to the supporting frames therefor, my more particular purpose being to provide a frame having relatively great strength and made up of parts easily and cheaply produced and standardized.

Reference is made to the accompanying drawings forming a part of this specification and in which like reference characters indicate like parts throughout the several figures.

Figure 1 is a fragmentary front elevation of the improvement.

Figure 2 is a horizontal cross section through one of the legs of the derrick and parts immediately associated therewith taken immediately above the bolt.

Figure 3 is a perspective view of one of the parts shown in Figure 2.

Figure 4 shows another form of my device.

A derrick frame is shown in Figure 1 provided with corner posts or legs 5, each made of an angle iron, as may be understood from Figures 2 and 4.

A clamp 13, having the form of an angle piece is fitted upon the outside of each leg 5. An extra reinforcing leg 16 extends from bottom to top of the tower. A skeleton plate 17 having one or more pairs of ribs 18, 19 and 20 integral with it and bent to different angles, as indicated in Figure 3, is placed within the angle leg 5 and the leg 16. A curved bolt 21, provided with a head 22 and a nut 23, extends through a hole 24^a in the skeleton plate 17, and also through holes in the clamp 13. When the nut 23 is tightened, so as to place the bolt under tension, the skeleton plate 17 is forced tightly toward the angle leg 5, so that the various ribs 18, 19 and 20 are jammed tightly against different portions of this angle leg. Thus a very secure joint is made and the brace thus arranged has considerable strength. In the event that the reinforcing plate 16 is omitted or of less thickness than that illustrated, the bolt 21 is extended through an opening 24^a to hold

the skeleton plate in position against the leg 5. Braces 14 are secured to the clamp 13, as indicated in Figure 1. Struts 15 are also secured to the clamp, being held in position by the curved bolts 21, as shown in Figure 2.

In case the skeleton plate shown in Figure 3 is not rigid enough for the purpose intended, I use in its place the member 38 shown in Figure 4.

In the form shown in Figure 4, the derrick leg appears at 25, and has as before the form of an angle iron. The clamp is shown at 26 and has a form of an angle plate, 70 provided with holes 27. Another angle leg member 37 is arranged on the inner face of the leg 5 to reinforce the same. The member 37 extends from the bottom to the top of the derrick. The clamping plate 38 has in 75 cross section a substantially arcuate form, and is provided with portions 39, projecting radially inward engaging the reinforcing leg 37. The leg 25 is provided with holes into which lugs 31 may extend for preventing relative displacement of the leg 25 and the clamp 26. A curved bolt 33, provided with a head 34 and a nut 35, extends through the holes 27 and also through holes in the braces or struts which are shown 80 at 36.

The curved portion of the clamping plate 38 is preferably grooved as shown to receive the bolt 33. The reinforcing leg 37 serves the double purpose of leg and clamp and it 90 may be made up of lengths of angle iron.

In the construction above described the various reinforcing members may be added without tearing down any portion of the original structure and without materially 95 changing the same.

If desirable, the said bolts may be threaded at both ends and nuts turned thereon instead of a solid head at one end.

I do not limit myself to the precise construction shown, as variations may be made therefrom without departing from the spirit of my invention.

Having thus described my invention what I desire to secure by Letters Patent is as 100 follows:

1. A device of the character described comprising a supporting leg having the general form of an angle iron, a clamp mounted upon said leg and having the form 110 of an angle-plate, and a second angle plate located within said leg and engaging the

inner surface thereof, said second-mentioned angle plate having a pair of straight sides, an intermediate bracing element between said sides and a curved bolt engaging said 5 intermediate element and said sides of said last mentioned angle plate.

2. A device of the character described comprising a supporting leg having the form of an angle plate, a clamp mounted 10 upon said supporting leg and having the form of an angle plate, a reinforcing leg fitted in and engaging said supporting leg and being in the form of an angle iron, a plate provided with ribs engaging the inner 15 surface of said reinforcing leg and a bolt extending through said clamp and plate provided with a nut.

3. A device of the character described comprising a supporting leg having a general form of an angle iron, a clamp mounted 20 upon said supporting leg and likewise having the form of an angle plate fitted on the outside of said angle iron, an angular reinforcing leg fitting in the supporting leg, 25 a skeleton plate provided with ribs engaging the inner surface of said reinforcing leg and a curved bolt extending through said clamp and through said skeleton plate so as to force said clamp and said skeleton 30 plate in opposite directions against the opposite faces of said plate.

4. A device of the character described comprising an angular supporting leg, a correspondingly shaped reinforcing leg fitting 35 in the supporting leg, an angular clamp fitting on the supporting leg, a member engaging the inner face of the re-inforcing leg, and a bolt passing through the clamp and engaging the said member.

40 5. A device of the character described comprising a supporting leg having a general form of an angle iron, a clamp mounted upon said supporting leg and likewise having the form of an angle iron, said clamp 45 being fitted on the outside of said angle iron first named, a reinforcing leg of angle iron within the supporting leg, a skeleton plate provided with ribs engaging the inner sur-

face of said reinforcing legs, said skeleton plate consisting of a flat plate cut from one 50 edge into parallel strips and bent alternately to each side at right angles to each other and intermediately left straight, and a bolt extending through said clamp mounted upon said supporting leg and through said 55 skeleton plate at the inner surface of said leg so as to force said clamp and said skeleton plate in opposite directions against the opposite faces of the reinforcing leg of angle iron.

60 6. A device of the character described comprising a supporting leg consisting of a plurality of sections secured end to end, each section having the form of an angle iron, a clamping plate fitted into said leg, another clamping plate fitted outside of said leg and secured thereto, a clamping and bracing member within said first-mentioned clamping plate and engaging the crotch of the angle and the sides thereof and a bolt 70 engaging said clamping and bracing member and extending through said second mentioned clamping plate, said bolt being adapted for connection of struts or girts thereto.

75 7. A device of the character described comprising a supporting leg having the form of an angle plate, a clamp mounted on said supporting leg and likewise having the form of an angle plate, said clamp being fitted on the outside of said supporting leg, 80 a reinforcing leg within the supporting leg, a skeleton plate provided with ribs engaging the inner surface of said reinforcing leg and an intermediate portion engaging the crotch of the angle of said leg, said 85 skeleton plate having portions bent in angular relation to each other and intermediately left straight, the bent portions engaging the sides of said reinforcing legs at the inner faces thereof, and a clamping member 90 connecting the sides of the clamp and skeleton plate and adapted for the connection of bracing means thereto outwardly of the clamp.

CHARLES DRAKE.
